NEGATIVE FEEDBACK AMPLIFIER

James Rowan Cannon, Liverpool, England, assignor to Automatic Telephone & Electric Company Limited, Liverpool, England, a company of Great Britain

Application November 16, 1943, Serial No. 510,545
In Great Britain January 6, 1943

1 Claim. (Cl. 179—171)

The present invention relates to negative feedback amplifiers and is more particularly concerned with push-pull amplifiers of the negative feedback type such as find particular use in multi-channel carrier telecommunication systems. The chief object of the invention is to provide a high performance multi-stage amplifier of the above-described type.

According to the invention, in a negative feedback amplifier of the multi-stage push-pull type, the inter-stage coupling choke or chokes and also the output transformer are provided with cores of magnetic material having suitable air-gaps to reduce harmonic distortion, the control grid bias potentials for at least one stage are derived from a resistance common to the cathodes of both valves of the stage to reduce spurious oscillation and all the valves employed are of the beam power tetrode type which are rendered satisfactorily interchangeable by the provision of an adjustment for the control grid bias potential of one valve of the pair.

The invention will be better understood from the following description of one method of carrying it into effect, reference being had to the accompanying drawings comprising Figs. 1 and 2 which when placed side by side show circuits of a two-stage push-pull negative feedback amplifier suitable for use in a multi-channel carrier frequency telephone system employing carrier frequencies up to 40 kilocycles per second.

Referring now to the drawings, it will be seen that the amplifier is of the choke capacity coupled type, while as regards the communication of the output to line, this is effected by a multi-winding transformer from which is derived the voltage feedback.

The circuit has been so designed that the amplifier will provide high performance when using beam power tetrodes throughout, for instance, of the international base type known as 6V6G which are characterised by the fact that the inherent harmonic distortion relates principally to the second harmonic which can be substantially balanced out in a push-pull circuit. The circuit arrangements are moreover such that these valves need not be in themselves perfectly matched as regards the curvature of their characteristic curves.

For the sake of simplification the valve filament circuits have been omitted as also have the valve testing circuits and supervision and alarm equipment which is usually provided on such amplifiers. The high tension voltage supply is connected up to terminals HT— and HT—, the posi-

tive high tension lead connecting with the screen grids of valves VA and VB via resistance YG, while it also connects via this resistance and then via choke LI which is centre-tapped, to the anodes of these valves. As regards the valves VC and VD, HT positive extends to the screen grids via the centre-tapped resistance YP and to the anodes via the centre-tapped primary winding of the output transformer OT. Condenser QA, located between the two stages, serves simply for decoupling purposes.

Considering now the operation of the amplifier, carrier frequency speech or other signals received at the input terminals 18, 11, are applied to potentiometer PA which is graduated in decibel (db.) steps and thence the applied voltage is extended via resistance YA to the primary winding of the input transformer IT. At transformer IT it divides between the two secondary windings and is applied to the control grids of valves VA and VB via the grid stopper resistances YB and YC, the standing bias potential on the control grids being derived from resistance YF which connects the cathodes of valves VA and VB with the high tension negative lead. The applied signal is amplified by valves VA and VB and is applied via the choke-capacity coupling including choke LI and condensers QB and QC to the control grids of the valves VC and VD of the second stage, resistances YK and YL serving as grid stoppers, and YH and YJ as leak resistances. On these two valves the standing grid bias potential is obtained by means of resistances YM and YN which are individually associated with the respective cathodes and which are by-passed respectively by condensers QE and QG to prevent unwanted negative feedback voltages from being developed across them. The function of variable resistance YO in circuit with the cathode of valve VD will be described later. The received amplified signal is further amplified by this pair of valves and delivered to the centre-tapped primary winding of the transformer OT. It will be noted in connection with these valves that by-pass condensers QD and QF are provided between the screen grids and cathodes to maintain the screen grids at cathode potential as far as the A. C. signal voltage is concerned.

As regards the output transformer, the amplified voltage appearing across the primary winding is communicated to the line winding and from there to the line output terminals 12 and 13. The centre winding is used for voltage feedback purposes and the voltage appearing across this winding is extended back to the outer ter-

minals of the equal resistances Y_C and Y_D . These connect via the centre-tapped resistance Y_E to the high tension negative lead and the feedback voltage is delivered via the input transformer secondary windings to the control grids of the valves VA and VB in the first push-pull stage where it functions in known manner partially to oppose the original input.

In order to obtain the desired degree of performance from the amplifier, it is necessary to prevent spurious oscillations being set up, while it is also necessary in order to avoid inter-channel interference to minimise harmonic distortion.

Spurious oscillation in a negative feedback amplifier may occur at a very high and/or a very low frequency, and even though the frequency concerned may lie outside the normal working range of the amplifier, its presence will seriously change the operating conditions of the valves and hence will affect the normal working of the amplifier. Such oscillation is usually due to the feedback having become positive instead of negative, for one thing as a result of the phase shift through the amplifier being different for different frequencies due to variation of impedances of inter-stage coupling transformers, etc. Thus the feedback at high and low frequencies may become 180° out of phase with that at the middle frequencies of the working frequency range, in other words the feedback at extremes of frequency becomes positive instead of negative. If the loop gain uB , where u and B are the complex transfer constants of the amplifier and feedback circuits respectively, becomes unity at these extreme frequencies where the angle of uB is zero, oscillation will occur. The exact criterion for stability is described by Nyquist in the "Bell System Technical Journal 1932," page 126.

Furthermore, the conventional method of obtaining automatic grid bias potential in a push-pull amplifier is by means of a voltage dropping resistance and associated by-pass condenser in the circuit of each valve cathode as is done in the high level second stage of the amplifier being described, the condensers serving to prevent the development of unwanted feedback voltages across the resistances. At high frequencies the condensers provide a shunt path of negligible impedance for the A. C. component of voltage across the biasing resistances so that there is no feedback of signal frequency to the associated valve grids and the phase of the anode currents is therefore not affected by the presence of the condensers. At lower frequencies, however, when the reactance of the condensers is no longer negligibly small compared with the resistances, the phase of the anode currents is given a shift in the leading sense by the condensers.

In the case of the first push-pull stage where this phase shift is additive with that produced by the high series impedance of the inter-stage coupling condensers and the low shunt reactance of transformers and chokes which also occurs at low frequency, it is found that by deriving the automatic grid bias for the valves VA and VB of this stage from common resistance Y_F the phase shift is minimised with a resultant increased stability. As regards the common bias resistance Y_F , there is no necessity to include a by-pass condenser, since, with the push-pull arrangement of valves the two A. C. components of the anode currents flowing therethrough are

substantially equal and opposite in phase and therefore no feedback voltage is developed. At the second push-pull stage, the phase shift effect is small compared with that of the first, so that it has not been considered necessary to employ the common bias resistance as in the first stage, but it is appreciated that it is in no sense essential to use a common bias resistor in the first stage only. The use of the conventional automatic bias arrangements for the second stage proves to be of convenience as will now be described.

In the low level push-pull stage, mismatch between the curvatures of the characteristic curves of the two valves concerned is not particularly serious from the point of view of harmonic distortion since the applied signal level and resultant grid swing is small. In the high-level stage, where large grid swings are concerned, the mismatch question is much more serious and here the effect of close limit matched valves is obtained by means of the variable resistance Y_O in the cathode circuit of valve VD , by means of which the working points on the characteristic curves of the two valves can be located on similar curvatures.

Considering further the reduction of harmonic distortion in a negative feedback amplifier, the use of current feedback ordinarily obtains this result. When, however, the output of the amplifier is taken via an output transformer, as is usual in carrier telephone circuits where a matched connection between the amplifier and line has to be made, it is necessary to use only voltage feedback, since if current feedback is used either alone or as well as voltage feedback, harmonic production may well be increased. The reason for this is that voltage feedback tends to maintain the output voltage sinusoidal which is the condition required but current feedback tends to maintain a sinusoidal current in the output transformer. Owing to the non-linear nature of the relationship between current and magnetic flux in the transformer iron circuit, this results in a non-sinusoidal output voltage with resultant harmonic distortion. On one test of an amplifier employing both voltage and current feedback, removal of the current feedback was found to improve the harmonic content by 10-15 db, and at the same time the gain was increased by about 2 db.

A further point as regards harmonic distortion is that in a push-pull amplifier using close limit matched valves and an accurately balanced circuit, all even harmonics are reduced to an extremely low level, and, owing to the careful balancing of valves it is usually assumed to be sufficient to design the iron circuits of push-pull chokes and transformers to carry a small percentage of the steady magnetising anode current of each valve, this catering for differential ageing of the valves, etc. It was found, however, that it was possible for substantial uni-directional current pulses applied to or produced in such a push-pull amplifier to cause unequal currents to flow momentarily in the two sides of the amplifier. This caused a small amount of permanent D. C. magnetisation of the iron cores to take place with consequent deterioration of the second harmonic distortion, which while of no account in a single channel amplifier, would be serious in a multi-channel amplifier because of inter-modulation effects. For this reason the cores of the inter-stage choke and of the output transformer have been made of the gapped type.

In an actual amplifier where the cathode bias resistances of the high level push-pull stage valves VC and VD are replaced by the windings of supervisory and alarm relays, if one of the relays was momentarily operated by hand the resultant momentary voltage induced in the winding was sufficient to cause a permanent deterioration of the second harmonic content of about 20 db due to D. C. magnetisation of the output transformer. The substitution of another transformer having a 10 butt joint air-gap was found to eliminate the effect entirely and no deterioration in harmonic content occurred even when one of the valves was removed and replaced while the amplifier was in operation.

As regards other details of the circuits which have not been described above, the resistance YA connected in series with the primary winding of the input transformer YD serves to further the margin against instability due to spurious oscillations by reducing the phase shift of the feedback voltage which occurs in the input transformer at low settings of the gain control potentiometer PA when the primary winding would normally be terminated, as far as locking-in to line from the 25 amplifier is concerned, by a low resistance. The resistance YA has a negligible effect on the amplifier gain. As regards resistance YQ in circuit with the output windings of transformer OT, this serves for loading matching purposes and is arranged in conjunction with a suitable turns ratio on the transformer so as to give the proper im-

pedance matching when looking in from the line and when looking out from the valves in the high level push-pull stage. Condenser QH across the output terminals 12 and 13 improves the stability of the amplifier and flattens the impedance and frequency response curves.

Tests which have been made on the amplifier described show that complete stability is obtainable even under conditions such as short-circuited 15 input and open-circuited output. The tests show further that there is no tendency to self-oscillation when an input and/or output valve was removed, either under normal or abnormal terminal conditions.

15. What I claim as new and desire to secure by Letters Patent is:

A negative feedback amplifier of the two-stage push-pull type employing choke capacity coupling in which the cores of the inter-stage coupling 20 choke and of the output transformer are provided with suitable air-gaps to reduce harmonic distortion, the control grid bias potentials for the first stage valves are derived from a resistance common to the cathodes of both valves to reduce spurious oscillation and all the valves employed 25 are of the beam power type which are rendered satisfactorily interchangeable in the second stage by the provision of separate resistances in the cathode circuits of the two valves with adjusting means for at least one of said resistances.

JAMES ROWAN CANNON.
